UNITED STATES PATENT OFFICE.

JEAN V. GIESLER, OF KNOXVILLE, TENNESSEE, ASSIGNOR TO THE FULTON COMPANY, OF KNOXVILLE, TENNESSEE, A CORPORATION OF MAINE.

COOLING SYSTEM FOR INTERNAL-COMBUSTION ENGINES.

1,318,069.

Specification of Letters Patent.

Patented Oct. 7, 1919.

Application filed November 22, 1917. Serial No. 203,362.

To all whom it may concern:

Be it known that I, JEAN V. GIESLER, a citizen of the United States of America, and a resident of Knoxville, Tennessee, have 5 invented a new and useful Improvement in Cooling Systems for Internal-Combustion Engines, which invention is fully set forth in the following specification.

This invention relates to cooling systems 10 for internal combustion engines, and while capable of application to a wide variety of engines of this type, has particular utility when applied to the cooling of an automobile engine.

15 It is an object of this invention to provide a cooling system for internal combustion engines with improved mechanism whereby the passage of air through the radiator and the flow of cooling medium through the system may be controlled to the end that the engine may operate under the most efficient 20 temperature conditions.

A further object of this invention is to 25 provide a cooling system for internal combustion engines having a radiator and a by-pass therearound with improved mechanism for controlling the flow of cooling medium through the radiator and by-pass and the passage of air through the radiator.

30 A further object of this invention is to provide a cooling system for internal combustion engines, comprising mechanism for controlling the flow of cooling medium through the system and mechanism for controlling the passage of air through the radiator, with improved means whereby 35 said mechanisms may be operated in succession by a common actuating device.

Another object of this invention is to 40 provide a cooling system for internal combustion engines, comprising means for controlling the flow of cooling medium through the system and means for controlling the passage of air through the radiator, with improved mechanism for operating said air-controlling means whereby relatively great power may be developed and an extended range of movement of said air-controlling means made possible.

50 Another object of this invention is to provide a cooling system for internal combustion engines, comprising mechanism for controlling the flow of cooling medium through the system and mechanism for con-

trolling the passage of air through the radiator, with thermosensitive means for actuating said mechanisms so constructed that, upon failure of the temperature control as by a leak in the thermosensitive vessel, said mechanisms shall automatically assume pre-determined positions of safety. 55

A further object relates to the provision of a cooling system of the type characterized which is simple in construction, inexpensive to manufacture and install, and efficient in 60 operation. 65

Other objects will appear as the description of the invention proceeds.

Stated broadly, the invention comprises a cooling system for internal combustion engines including a radiator, a valve for controlling the flow of cooling medium through said radiator, means for controlling the passage of air through said radiator, an auxiliary system for circulating a fluid, and 70

means in the form of a pressure motor operated by the pressure developed in said circulating system for operating said air-controlling means. In the form shown, said system is provided with a by-pass around 75

said radiator and a valve for closing said by-pass simultaneously with and proportionately to the opening of the valve controlling the flow of cooling medium through the radiator. To regulate the pressure 80

transmitted to the pressure motor, a valve is provided in said auxiliary circulating system and a common actuating means is provided for all said valves, said actuating 85

means being shown as a thermosensitive device. To enable the valve in the auxiliary circulating system to regulate the pressure transmitted to the pressure motor after the valve mechanism controlling the flow of the cooling medium through the radiator and by-pass has operated, said valve mechanism, in the form shown, comprises a movable valve seat for coaction with the valve member controlling the flow of cooling medium through the by-pass, whereby, although said 90

valve member is in engagement with said valve seat and the passage through said by-pass closed, the valve in said auxiliary circu-

lating system may continue to move to 100

regulate the pressure developed in said system and thereby effect the operation of said air-controlling means. 105

The invention is capable of receiving a

variety of mechanical expressions, one of which is shown on the accompanying drawings, but it is to be expressly understood that said drawings are for purposes of illustration only and are not to be construed as a definition of the limits of the invention, reference being had to the appended claims for that purpose.

Referring in detail to said drawings, 10 wherein the same characters of reference designate corresponding parts in the several figures,—

Figure 1 is a schematic elevation, partly in section, of so much of a cooling system of 15 an internal combustion engine embodying the present invention as is necessary to an understanding of the same;

Figs. 2 and 3 are fragmentary views illustrating different positions assumed by the 20 valves.

In the form shown, 1 is a radiator of any suitable construction, 2 the upper water line leading from the engine jacket or jackets (not shown) to said radiator, and 3 the 25 lower water line leading from said radiator to the circulating pump 4 which communicates through conduit 5 with said jacket or jackets.

Means are provided for controlling the 30 passage of air through said radiator, said means being of any suitable construction. In the form shown, a plurality of shutters 6 are pivotally mounted within a housing 7 designed to be received over the front of 35 the radiator, said shutters 6 being pivotally connected to a common actuating bar or rod 8. It will be understood, however, that in place of shutters, a damper, curtain or any other suitable device for controlling the passage 40 of air through the radiator may be employed in place of the shutters shown.

In the form shown, a by-pass is provided around the radiator 1, said by-pass comprising a conduit 9 communicating at its upper 45 end with the upper water line 2 and at its lower end with a thermostat housing 10 provided with a transverse conduit therethrough as shown at 11—12, which conduit is connected into and constitutes a part of the lower water line 3. Conduit 9 may desirably be heat-insulated so that the water flowing into the thermostat housing therethrough shall have substantially the same temperature as that at which it leaves the 50 engine jacket or jackets and flows through the upper water line 2.

Thermostat housing 10 is shown as divided into two chambers by a transverse partition 13, the upper chamber 14 being of 55 such size and conformation as to receive the thermostat to be hereinafter described and provide space between the periphery of said thermostat and the wall of the chamber for the proper circulation of the water. The lower chamber constitutes the transverse

conduit 11—12 and, in the form shown, is provided with a pair of valve seats 15 and 16 through which the two sections of said conduit 11—12 communicate. Mounted for rectilinear movement within an aperture 17 70 provided in the partition 13 is a flanged valve seat 18 normally urged to the position shown in Fig. 1 by a spring 19.

Mounted within the chamber 14 is a thermostat which may be of any suitable construction. In accordance with the preferred embodiment of the invention, said thermostat takes the form of an expandable and contractible corrugated resilient vessel 20 provided with a stationary end wall 21 fixedly 80 mounted in position by any suitable means, as by a screw-threaded boss 22 received within an aperture in a bracket 23 positioned within said chamber, the opposite and movable end wall 24 of said vessel being provided with a valve stem 25 connected to a pair of seating valves 26 and 27 adapted to open and close the ports 15 and 16 respectively. Vessel 20 is preferably charged with a volatile thermosensitive fluid at a 90 pressure below that to which said vessel is exteriorly subjected, whereby said vessel is normally contracted against the elasticity inherent in the resilient walls of the vessel. It is apparent, however, that in place of a 95 vessel constructed with resilient walls, a vessel having non-resilient walls but provided with an exterior or interior spring to give the requisite resiliency could be substituted therefor.

To operate the shutters, a pressure motor is provided in an auxiliary fluid-circulating system. Said system may take a variety of forms and employ any suitable fluid, and may, under some circumstances, be a system 10. with which an automobile engine is normally provided, such for example as the system for circulating lubricating oil. In the embodiment illustrated, however, this circulating system is made adjunctive to the cooling system and the cooling medium is the fluid circulated therethrough. In the form shown, a pipe 28 communicates with the interior of thermostat chamber 14 at one end and with a suitable circulating pump 11. 29 at its opposite end. Said pump may be driven by a separate motor but, as shown, is preferably driven from the driving shaft of pump 4. A second pipe 30 communicates at one end with the pump 29 and at its opposite end with one branch of a T-coupling 31. From the opposite branch of said T-coupling 31 a pipe 32 leads to the interior of a cylinder 33 in which works a piston 34 provided with a cup-leather packing 35. 120 Piston rod 36 is connected through bell-crank 37 with the operating bar 8 of the shutters 6. In the form shown, a spring 38 is connected to said bell-crank 37 and to a suitable adjusting screw 39 mounted in the 130

wall of the shutter housing 7, said spring normally opposing the opening of the shutters. The third branch of said T-coupling 31 communicates through pipe 40 and port 41 with the interior of an extension 42 of the thermostat housing, which extension is in open communication with section 12 of the transverse conduit through said housing. To control said port 41, a valve member 43 is mounted upon or formed integrally with valve stem 25.

Operation: When the engine is started, the cooling medium in the cooling system is at a relatively low temperature, vessel 20 is contracted, its movable end wall 24 is removed from movable valve seat 18, valve members 26 and 27 are in engagement with valve ports 15 and 16 respectively, and valve member 43 is remote from valve port 41, all as shown in Fig. 3. In this position of the parts, the pump 4 forces the cooling medium through conduit 5, the engine jacket or jackets, the upper water line 2, by-pass 9, thermostat chamber 14, conduit 12, and lower water line 3. As valve members 26 and 27 are in engagement with their respective seats, no cooling medium is flowing through the radiator. Pump 29 also draws cooling medium from thermostat chamber 14 through pipe 28 and forces the same through pipe 30, T-coupling 31, pipe 40, to extension 42 of the thermostat housing, where it returns to the cooling system through conduit 12. Spring 38 maintains the shutters 6 closed and piston 34 is at the inner end of the cylinder, the flow of cooling medium through the auxiliary circulating system having no effect upon said piston.

As the engine continues to run, the cooling medium rapidly rises in temperature as said medium is subjected to substantially no cooling influence. When the cooling medium reaches that temperature at which the engine operates most efficiently and tends to rise above said temperature, vessel 20 begins to expand, its end wall 24 approaching valve seat 18 and valve members 26 and 27 being withdrawn from valve seats 15 and 16 respectively. Part of the cooling medium now flows through the radiator 1 and back to the pump 4 through the sections 11 and 12 of the transverse conduit in the thermostat housing. Since movable end wall 24 of vessel 20 approaches valve seat 18 as valve members 26 and 27 are withdrawn from their respective seats 15 and 16, the flow of cooling medium through the by-pass is reduced in proportion to the increase of the flow of cooling medium through the radiator. Danger of overheating of the engine, owing to a large quantity of fluid at high temperature flowing through an always-open by-pass, is thereby prevented. Opening of the valve ports 15 and 16 is accompanied by movement of valve member 43

toward port 41, but said valve member does not approach said port sufficiently to reduce the effective area of the opening, whereby such movement has no effect upon the pressure in the auxiliary circulating system in communication with the pressure motor. If the temperature of the cooling medium continues to rise, vessel 20 continues to expand until its movable end wall 24 engages valve seat 18 cutting off the flow of cooling medium therethrough and opening wide the ports 15 and 16. In this position of the parts, all of the cooling medium is forced through the radiator.

If the temperature of the cooling medium continues to rise, vessel 20 continues to expand, valve seat 18 moving against the tension of spring 19 to permit such further expansion. This further movement of movable end wall 24 of said vessel 20 brings valve member 43 into proximity to or engagement with port 41, as shown in Fig. 2, thereby restricting or cutting off the flow of cooling medium from pipe 40 into extension 42 of the thermostat housing. Pump 29 therefore builds up a pressure in the auxiliary circulating system between said pump and said port, which pressure is transmitted through pipe 32 to the interior of cylinder 33, causing piston 34 to move against the tension of spring 38 to open the shutters 6 and permit the passage of air through said radiator to further cool the medium flowing therethrough. The extent of opening of said shutters depends on the extent of pressure built up in said circulating system, which pressure in turn depends upon the proximity of valve member 43 to port 41 as determined by the degree of expansion of vessel 20.

Upon a drop in temperature of the cooling medium, a reverse sequence of operations occurs, the shutters first closing and the valve members 26 and 27 subsequently preventing the circulation of cooling medium through the radiator.

It will be observed that, by opposing the opening of the shutters with a spring and restricting the valve opening in the auxiliary system in communication with the pressure motor only after the valve members have operated to entirely close the by-pass and open wide the passage through the radiator, all of the cooling medium is forced to flow through the radiator before the shutters begin to open to admit air to said radiator. Thereby such medium is subjected to the greater cooling influence of the radiator before the shutters are operated, and this additional cooling influence may, in cold weather, be sufficient to maintain said medium at that temperature at which the engine operates most efficiently. In case such additional cooling influence is not sufficient, however, the shutters are

opened promptly to such an extent and to admit so much air as will maintain the cooling medium at its proper temperature. Furthermore, by proportionately decreasing the flow of cooling medium through the by-pass as the flow of cooling medium through the radiator is increased, no large quantity of cooling medium at a high temperature is flowing through an always-open by-pass to maintain the temperature of such medium as it flows through the jackets at too high a temperature, nor is the effective area through the system so varied by opening up the passage through the radiator as to adversely affect the operation of the circulating pump. By connecting the auxiliary circulating system with the interior of the thermostat chamber 14, it will also be observed that, even when vessel 20 has expanded so as to close the port in valve seat 18, there is still a circulation of the cooling medium through the thermostat chamber at a temperature substantially that at which it leaves the engine jacket whereby said thermostat will respond promptly to a drop in temperature. Furthermore, by the use of the piston 34, a relatively long throw is permitted to the member which operates the shutters, which is available not only to open the shutters wide but may be used for operating air-controlling devices such as dampers or curtains which require a relatively long movement of their operating members.

While the embodiment of the invention shown on the drawings has been described with considerable particularity, it is to be expressly understood that the invention is not to be restricted thereto, since the same is capable of receiving a variety of mechanical expressions some of which will readily suggest themselves to those skilled in the art, while certain features thereof are capable of use without other features thereof. Reference is therefore to be had to the claims hereto appended for a definition of the limits of the invention.

What is claimed is:—

1. In a cooling system for internal combustion engines, a radiator, means for controlling the passage of air through said radiator, a valve for controlling the flow of cooling medium through said radiator, an auxiliary system for circulating a fluid, and means controlled by the pressure in said auxiliary circulating system for operating said air-controlling means.

2. In a cooling system for internal combustion engines, a radiator, means for controlling the passage of air through said radiator, a valve for controlling the flow of cooling medium through said radiator, an auxiliary system for circulating a fluid, means controlled by the pressure in said auxiliary circulating system for operating

said air-controlling means, and means for regulating the pressure in said auxiliary circulating system.

3. In a cooling system for internal combustion engines, a radiator, means for controlling the passage of air through said radiator, a valve for controlling the flow of cooling medium through said radiator, a system for circulating a fluid, means controlled by the pressure in said circulating system for operating said air-controlling means, means for regulating the pressure in said circulating system, and a common actuating means for said valve and said pressure-regulating means.

4. In a cooling system for internal combustion engines, a radiator, means for controlling the passage of air through said radiator, a valve for controlling the flow of cooling medium through said radiator, a system for circulating a fluid, means controlled by the pressure in said circulating system for operating said air-controlling means, means for regulating the pressure in said circulating system, and a thermosensitive device for operating said valve and said pressure-regulating means.

5. In a cooling system for internal combustion engines, a radiator, means for controlling the passage of air therethrough, a by-pass around said radiator, valve mechanism for controlling the flow of cooling medium through said radiator and by-pass, a system for circulating a fluid, means controlled by the pressure in said circulating system for operating said air-controlling means, and means for regulating the pressure in said system.

6. In a cooling system for internal combustion engines, a radiator, means for controlling the passage of air therethrough, a by-pass around said radiator, valve mechanism for controlling the flow of cooling medium through said radiator and by-pass, a system for circulating a fluid, means controlled by the pressure in said circulating system for operating said air-controlling means, means for regulating the pressure in said circulating system, and a common actuating means for said valve mechanism and said pressure-regulating means.

7. In a cooling system for internal combustion engines, a radiator, means for controlling the passage of air therethrough, a by-pass around said radiator, valve mechanism for controlling the flow of cooling medium through said radiator and by-pass, a system for circulating a fluid, means controlled by the pressure in said circulating system for operating said air-controlling means, means for regulating the pressure in said circulating system, and a thermosensitive device for operating said valve mechanism and said pressure-regulating means.

8. In a cooling system for internal com-

bustion engines, a radiator, means for controlling the passage of air therethrough, a pressure motor for operating said means, a system for circulating a fluid in operative 5 relation to said pressure motor, a valve in said circulating system, a valve for controlling the flow of cooling medium through said radiator, and thermosensitive means for operating said valves.

10 9. In a cooling system for internal combustion engines, a radiator, means for controlling the passage of air therethrough, a pressure motor for operating said means, a system for circulating a fluid in operative 75 15 relation to said pressure motor, a valve in said circulating system, a by-pass around said radiator, valve mechanism for controlling the flow of cooling medium through said radiator and by-pass, and thermosensitive means for operating said valves.

20 10. In a cooling system for internal combustion engines, a radiator, means for controlling the passage of air therethrough, a pressure motor for operating said means, a system for circulating a fluid in operative 80 25 relation to said pressure motor, a valve in said circulating system, a valve for controlling the flow of cooling medium through said radiator, and thermosensitive means 90 connected to said valves to operate the same in succession.

30 11. In a cooling system for internal combustion engines, a radiator, means for controlling the passage of air therethrough, a pressure motor for operating said means, a system for circulating a fluid in operative 95 35 relation to said pressure motor, a valve in said circulating system, a by-pass around said radiator, valve mechanism for controlling the flow of cooling medium through said radiator and by-pass, and thermosensitive means connected to said valves to operate the same in succession.

40 12. In a cooling system for internal combustion engines, a radiator, means for controlling the passage of air therethrough, a valve for controlling the flow of cooling medium through said radiator, a system for circulating a fluid, means controlled by the pressure in said circulating system for operating said air-controlling means, means for regulating the pressure in said circulating system, and means connected to said valve and pressure-regulating means to cause the 100 50 operation of the same in succession.

55 13. In a cooling system for internal combustion engines, a radiator, means for controlling the passage of air therethrough, a valve for controlling the flow of cooling medium through said radiator, a system for circulating a fluid, means controlled by the pressure in said system for operating said air-controlling means, means for regulating the pressure in said circulating system, and a thermosensitive device connected to 105 60 65

said valve and said pressure-regulating means to cause the operation of the same in succession.

14. In a cooling system for internal combustion engines, a radiator, means for controlling the passage of air therethrough, a valve for controlling the flow of cooling medium through said radiator, a pressure motor for operating said air-controlling means, a system for circulating a fluid in 75 operative relation to said pressure motor, a valve in said circulating system, and a common actuating means for operating said valves in succession.

15. In a cooling system for internal combustion engines, a radiator, means for controlling the passage of air therethrough, a by-pass around said radiator, valve mechanism for controlling the flow of cooling medium through said radiator and by-pass, a system for circulating a fluid, means controlled by the pressure in said system for operating said air-controlling means, means for regulating the pressure in said circulating system, and means connected to said 90 valve and pressure-regulating means to cause the operation of the same in succession.

16. In a cooling system for internal combustion engines, a radiator, means for controlling the passage of air therethrough, a by-pass around said radiator, valve mechanism for controlling the flow of cooling medium through said radiator and by-pass, a system for circulating a fluid, means controlled by the pressure in said system for operating said air-controlling means, means for regulating the pressure in said circulating system, and a thermosensitive device 100 105 connected to said valve and pressure-regulating means to cause the operation of the same in succession.

17. In a cooling system for internal combustion engines, a radiator, means for controlling the passage of air therethrough, a by-pass around said radiator, valve mechanism for controlling the flow of cooling medium through said radiator and by-pass, a pressure motor for operating said air-controlling means, a system for circulating a fluid in operative relation to said pressure motor, a valve in said circulating system, and a common actuating means for operating said valves in succession.

18. In a cooling system for internal combustion engines, a radiator, means for controlling the passage of air therethrough, a by-pass around said radiator, valve mechanism for controlling the flow of cooling medium through said radiator and by-pass, a system for circulating a fluid, means controlled by the pressure in said circulating system for operating said air-controlling means, means for regulating the pressure in said circulating system, and a common 110 115 120 125 130

actuating means for operating said valve mechanism to proportionately close said by-pass and open the passage through said radiator and thereafter operating said pressure-regulating means to open said air-controlling means.

19. In a cooling system for internal combustion engines, a radiator, means for controlling the passage of air therethrough, a by-pass around said radiator, valve mechanism for controlling the flow of cooling medium through said radiator and by-pass, a system for circulating a fluid, means controlled by the pressure in said circulating system for operating said air-controlling means, means for regulating the pressure in said circulating system, and thermosensitive means for operating said valve mechanism to proportionately close said by-pass and open the passage through said radiator and thereafter operating said pressure-regulating means to open said air-controlling means.

20. In a cooling system for internal combustion engines, a radiator, means for controlling the passage of air therethrough, a by-pass around said radiator, valve mechanism for controlling the flow of cooling medium through said radiator and by-pass, a pressure motor for operating said air-controlling means, a system for conveying a pressure-fluid to said pressure motor, a valve in said system for controlling the pressure transmitted to said pressure motor, and thermosensitive means for operating said valves in succession.

21. In a cooling system for internal combustion engines, a radiator, means for controlling the passage of air therethrough, a valve for controlling the flow of cooling medium through said radiator, a pressure motor for operating said air-controlling means, a system for circulating a fluid in operative relation to said pressure motor, a valve in said system for controlling the pressure transmitted to said pressure motor, and thermosensitive means for operating said valves in succession.

22. In a cooling system for internal combustion engines, a radiator, means for controlling the passage of air therethrough, a pressure motor for operating said means, a valve for regulating the pressure transmitted to said pressure motor, a by-pass around said radiator, valve mechanism for controlling the flow of cooling medium through said radiator and by-pass, and a connection between said valve and said valve mechanism, said valve mechanism including a movable valve seat whereby said valve may regulate the pressure transmitted to said pressure motor after said valve mechanism has closed said by-pass.

23. In a cooling system for internal combustion engines, a radiator, means for con-

trolling the passage of air therethrough, a pressure motor for operating said means, a valve for regulating the pressure transmitted to said pressure motor, a by-pass around said radiator, valve mechanism for controlling the flow of cooling medium through said radiator and by-pass, and a thermosensitive device connected to said valve and said valve mechanism for operating the same, said valve mechanism including a movable valve seat whereby said valve may regulate the pressure transmitted to said pressure motor after said valve mechanism has closed said by-pass.

24. In a cooling system for internal combustion engines, a radiator, means for controlling the passage of air therethrough, a pressure motor for operating said means, a valve for regulating the pressure transmitted to said pressure motor, a by-pass around said radiator, connected valves for simultaneously closing said by-pass and opening the passage through said radiator, and thermosensitive means connected to all said valves, said by-pass valve having a movable valve seat whereby after said by-pass is closed said first-named valve may regulate the pressure transmitted to said pressure motor and effect the operation of said air-controlling means.

25. In a cooling system for internal combustion engines, a radiator, means for controlling the passage of air through said radiator, a by-pass around said radiator, a valve to control the flow of cooling medium through said by-pass, said valve having a spring-pressed valve seat, a valve for controlling the flow of cooling medium through said radiator, a pressure motor for operating said air-controlling means, a system for circulating a fluid in operative relation to said pressure motor, a valve in said circulating system, and a common actuating means for all said valves, said valve seat moving after said by-pass is closed and the passage through said radiator is open to enable said last-named valve to regulate the degree of pressure transmitted to said pressure motor.

26. In a cooling system for internal combustion engines, a radiator, means for controlling the passage of air through said radiator, a pressure motor for operating the same, a valve for regulating the pressure transmitted to said pressure motor, a by-pass around said radiator, valve mechanism for controlling the flow of cooling medium through said radiator and by-pass, and means connecting said valve and said valve mechanism to move in unison, said valve mechanism having a movable valve seat to enable said first-named valve to regulate the transmission of pressure to said pressure motor after said valve mechanism has closed said by-pass and opened the passage through said radiator.

27. In a cooling system for internal combustion engines, a radiator, means for controlling the passage of air therethrough, a valve for controlling the flow of cooling medium through said radiator and having a position of safety, a pressure motor for operating said air-controlling means, a system for circulating a fluid in operative relation to said pressure motor, a valve in said system adapted in one position to cause said pressure motor to move said air-controlling means to safety position, and thermosensitive means for operating said valves, said thermosensitive means having an inherent tendency to move said valves to their respective safety positions upon the occurrence of a leak in said thermosensitive means. 65
28. In a cooling system for internal combustion engines, a radiator, means for controlling the passage of air therethrough, a valve for controlling the flow of cooling medium through said radiator and having a position of safety, a pressure motor for operating said air-controlling means, a system for circulating a fluid in operative relation to said pressure motor, a valve in said system adapted in one position to cause said pressure motor to move said air-controlling means to safety position, a by-pass around said radiator, a valve for controlling the flow of cooling medium through said by-pass and having a position of safety, and thermosensitive means for operating said valves, said thermosensitive means having an inherent tendency to move said valves to their respective safety positions upon the occurrence of a leak in said thermosensitive means. 70
29. In a cooling system for internal combustion engines, a radiator, means for controlling the passage of air therethrough, a valve for controlling the flow of cooling medium through said radiator, a piston for operating said air-controlling means, a system for circulating a fluid in operative relation to said piston, a valve in said system for regulating the degree of pressure transmitted to said piston, and a common actuating means for said valves. 75
30. In a cooling system for internal combustion engines, a radiator, means for controlling the passage of air therethrough, a by-pass around said radiator, valve mechanism for controlling the flow of cooling medium through said by-pass and having a position of safety, a pressure motor for operating said air-controlling means, a valve for regulating the pressure transmitted to said pressure motor, and a common actuating means for said valves. 80
31. In a cooling system for internal combustion engines, a radiator, means for controlling the passage of air therethrough, a valve for controlling the flow of cooling medium through said radiator, a pressure motor for operating said air-controlling means, a system for conveying a pressure-fluid to said pressure motor, a valve in said system for controlling the pressure transmitted to said pressure motor, and a common actuating means for said valves. 85
32. In a cooling system for internal combustion engines, a radiator, means for controlling the passage of air therethrough, a by-pass around said radiator, valve mechanism for controlling the flow of cooling medium through said radiator and by-pass, a pressure motor for operating said air-controlling means, a system for conveying a pressure-fluid to said pressure motor, a valve in said system for controlling the pressure transmitted to said pressure motor, and thermosensitive means for actuating said valves. 90
33. In a cooling system for internal combustion engines, a radiator, means for controlling the passage of air therethrough, a valve for controlling the flow of cooling medium through said radiator, a pressure motor for operating said air-controlling means, a valve for regulating the pressure transmitted to said pressure motor, and a common actuating means for said valves. 95
34. In a cooling system for internal combustion engines, a radiator, means for controlling the passage of air therethrough, a valve for controlling the flow of cooling medium through said radiator, a pressure motor for operating said air-controlling means, a valve for regulating the pressure transmitted to said pressure motor, and thermosensitive means for actuating said valves. 100
35. In a cooling system for internal combustion engines, a radiator, means for controlling the passage of air therethrough, valve mechanism for controlling the flow of the cooling medium through said system, thermosensitive means for operating said valve mechanism, a pressure motor for operating said air-controlling means, and an auxiliary system for circulating the cooling medium in operative relation to said pressure motor, said auxiliary system having an inlet adjacent said thermosensitive means whereby there is circulation of said cooling medium past said thermosensitive means at all times. 110
- In testimony whereof I have signed this specification.
- JEAN V. GIESLER.
